Patented May 11, 1976

239,864

INDUSTRIAL APPARATUS FOR MILLING SOLID PARTICLES WITHIN A LIQUID SLURRY

Edward J. Szkaradek, Santa Ana, Calif., assignor to
Morehouse Industries, Inc., Fullerton, Calif.

Filed Dec. 4, 1974, Ser. No. 529,299

Term of patent 14 years

Int. Cl. D15—09

U.S. Cl. D55—1 B

FIG. 1 is a front, top perspective view of the industrial apparatus for milling solid particles within a liquid slurry;

FIG. 2 is a side elevational view thereof; and

FIG. 3 is a rear elevational view.

I claim:

The ornamental design for an industrial apparatus for milling solid particles within a liquid slurry, as shown.
